CLAIM

The ornamental design for a beverage can, as shown and described.

DESCRIPTION

FIG. 1 is a front elevation view of a beverage can showing our new can;

FIG. 2 is a rear elevation view thereof;

FIG. 3 is a left-side elevation view thereof;

FIG. 4 is a right-side elevation view thereof;

FIG. 5 is a top plan view thereof; and,

FIG. 6 is a bottom plan view thereof.

The broken line circles shown in FIGS. 5 & 6 which define the boundaries of the claimed design, form no part thereof. The broken line showing of environment of the tab closure shown in FIG. 5 is for illustrative purposes only and forms no part of the claimed design.

1 Claim, 3 Drawing Sheets
